UNITED STATES PATENT OFFICE.

EZRA E. SMART AND GEORGE H. HART, OF HARTFORD, CONNECTICUT, ASSIGNEES TO THE HART MANUFACTURING COMPANY, OF HARTFORD, CONNECTICUT, A CORPORATION OF NEW JERSEY.

SWITCH.

1,098,849.

Specification of Letters Patent. Patented June 2, 1914.

Application filed November 26, 1913. Serial No. 803,164.

To all whom it may concern:

Be it known that we, EZRA E. SMART and GEORGE H. HART, citizens of the United States, residing at Hartford, Hartford county, and State of Connecticut, have invented certain new and useful Improvements in Switches, of which the following is a full, clear, and exact description.

Our invention relates to improvements in switches and has for its object to provide new and improved push and pull snap switch of the type shown in patent to Gibbs and Perkins, No. 436,080 granted September 9, 1890, the object being to provide anti-friction rollers for engaging the cam surfaces so as to insure an efficient action and to provide new and improved contact making members for making and breaking the circuit.

20 The following is a description of the invention, reference being had to the accompanying drawings, in which:

Figure 1 shows a longitudinal section of the switch embodying our invention with the parts in open position. Fig. 2 shows a similar view with the parts in closed position. Fig. 3 shows a top plan view of the switch arm. Fig. 4 shows a bottom plan view of the switch arm. Fig. 5 shows a section of the switch arm on the line $\alpha-\alpha$ Fig. 4. Fig. 6 shows a top plan view of the base carrying the circuit terminals. Fig. 7 shows a side elevation of the same. Fig. 8 shows a side elevation of the actuating member. Fig. 9 shows an end elevation of the actuating member. Fig. 10 shows a plan view of one of the anti-friction bearing members. Fig. 11 shows an end view of the same.

40 Referring more particularly to the drawings, 1 is a face plate to which is connected a casing 2, having at its inner end an insulating block or base 3, and at its outer end an insulating base 4. This insulating base 45 carries stationary contacts 5-5' which are connected to circuit terminals 6-6' provided with binding posts 7-7'. The base is secured to the casing by pins 8-8'. The base 3 is provided with a metallic bushing 9 having a slot 10. The plunger 11 has cams provided with oppositely sloping cam surfaces 12-12', and passes through the face plate 1 and into the bushing 9. The cam surfaces have extensions 13 which enter the slots 10 in the bushing, so as to prevent the

actuating member from being turned axially. Surrounding the plunger 11 is a movable switch arm having two concentric cup shaped contact portions 14-14', the sides of which are cut away so as to leave oppositely disposed contact surfaces for engagement with the contacts 5-5', these contact portions being divided by slots 15 so as to result in the plurality of relatively movable, flexible arms. The ends of the arms on one cup shaped member, engage the inner surfaces of the contacts 5-5' respectively, and the ends of the arm on the contact member engaging the outer surfaces of said contacts 5-5' respectively, when the switch is closed. At the bottom of the cup shaped member and separated therefrom by a perforating insulating disk 16, is a support 17. This support is held in position by inturned tangs 18 carried by the outer cup shaped member 14, a disk of insulating material 19 being inserted between the member 17 and the tangs 18, so as to insulate the support from the tangs and from the cupped members. This support 17 has a U-shaped portion 20 which is provided in each of its limbs with laterally extending slots 21, and has an opening 22 through which the plunger 11 and the cam surfaces 12-12' pass. Between the upright sides of the U-shaped portions 20 of the support 17, are two anti-friction rollers 23, having shafts 24-24' which extend through the slots 21. The shafts of the two rollers are parallel to each other. The corresponding ends of the two shafts 24-24 and 24'-24' are connected by tension springs 25-25' respectively. These springs are parallel to each other and act to draw the rollers 23 toward one another, causing them to act in conjunction with the cam surfaces 12-12'. For convenience in manufacture, I use ordinary tension coil springs although the particular form of spring plays no function in my combination. The cam surfaces 12-12' are each inclined in opposite directions.

45 The action of the switch is as follows: The handle 11' moves the cam surfaces 12-12' so as to cause them to separate the anti-friction rollers 23 and increase the tension of the springs 25-25'. When the handle 11', Fig. 1, is pulled to its limit the high points of the cams pass beyond the axes of the shafts of the anti-friction rollers 23, wheretupon the tension spring 25-

25', tending to draw the anti-friction rollers together, cause the anti-friction rollers to move along the cam toward the base plate 4. The anti-friction rollers being connected to the switch arm, so that these parts move together longitudinally along the axis of the plunger 11, carry the switch arm with them so as to cause it to engage the contacts 5-5' and close the switch, the part being then in the position shown in Fig. 2. When the parts are in the position shown in Fig. 2, the pressure upon the handle 11' causes the plunger 11, together with the cam surfaces 12-12 to move toward the base 4, until the high points of the cam pass beyond the axes of the shafts 24-24', whereupon the reverse action takes place, the anti-friction rollers traveling down the cam surfaces which are inclined toward the handle 11', and carrying the switch arm into open position as shown in Fig. 1.

The contact surfaces 5-5' are curved, so as to correspond to the curve of the wall of the cup shaped members. The surfaces of the contact members 5-5' opposing the cup shaped members, are inclined or wedge shaped, and the portions of the cup shaped members which engage with the contacts are bent away from one another so as to form with the wedge shaped openings for engagement therewith, thus insuring an ample electrical engagement with parts of relatively small dimensions.

The action of the switch both on closing and opening, is a free quick snap action, being due to the fact that the anti-friction rollers 23-23 have no movement, which is independent of the switch arm, longitudinally of the plunger 11, and are forced toward the opposite inclined cam surfaces 12-12 by the springs 25-25'.

As will be evident to those skilled in the art, our invention permits of various modifications without departing from the spirit thereof or the scope of the appended claims.

What we claim is:

1. In a switch, the combination of stationary switch contacts, adapted to be electrically connected to circuit conductors, a movable switch arm for electrically connecting and disconnecting said contacts, a plunger passing through said switch arm, a cam having oppositely inclined cam surfaces carried by said plunger, an anti-friction roller carried by said switch arm, said switch arm and roller moving with each other longitudinally of said plunger, said roller having a movement independent of said switch arm in a direction transverse to the axis of said plunger, shafts extending from the ends of said roller and through transverse openings in said switch arm, and springs engaging the ends of said shaft, and tending to move said roller toward said plunger.

65 2. In a switch, the combination of station-

ary contacts, adapted to be electrically connected to circuit conductors, a movable switch arm for electrically connecting and disconnecting said contacts, a plunger passing through said switch arm, a cam having two pairs of oppositely inclined cam surfaces carried by said plunger and two parallel anti-friction rollers carried by said arm, said switch arm and rollers moving with each other longitudinally of said plunger, said rollers each having a movement independent of said switch arm in a direction transverse to the axis of said plunger, shafts extending from the ends of said rollers and through transverse openings in said switch arm, and springs engaging the ends of said shafts and tending to move said rollers toward the plunger.

3. In a switch, the combination of stationary contacts, adapted to be electrically connected to circuit conductors, a movable switch arm for electrically connecting and disconnecting said contacts, a plunger passing through said switch arm, a cam having two pairs of oppositely inclined cam surfaces carried by said plunger and two parallel anti-friction rollers carried by said arm, said switch arm and rollers moving with each other longitudinally of said plunger, said rollers each having a movement independent of said switch arm in a direction transverse to the axis of said plunger, shafts extending from the ends of said rollers and through transverse openings in said switch arm, and two parallel springs engaging the ends of said shafts and tending to move said rollers toward the plunger.

4. In a switch, the combination of stationary switch contacts, adapted to be electrically connected to circuit conductors, a movable switch arm for electrically connecting and disconnecting said contacts, a plunger passing through said switch arm, a cam having oppositely inclined cam surfaces carried by said plunger, an anti-friction roller carried by said switch arm, said switch arm and roller moving with each other longitudinally of said plunger, said roller having a movement independent of said switch arm in a direction transverse to the axes of said plunger, shafts extending from the ends of said roller and through transverse openings in said switch arm, and springs engaging the ends of said shaft and tending to move said roller toward said plunger, said switch arm having yielding contact arms extending parallel to the axis of said plunger and arranged in arcs of a circle.

5. In a switch, the combination of stationary switch contacts, adapted to be electrically connected to circuit conductors, a movable switch arm for electrically connecting and disconnecting said contacts, a plunger passing through said switch arm, a cam having oppositely inclined cam surfaces carried

by said plunger, an anti-friction roller carried by said switch arm, said switch arm and roller moving with each other longitudinally of said plunger, said roller having a movement independent of said switch arm in a direction transverse to the axis of said plunger, shafts extending from the ends of said roller and through transverse openings in said switch arm, and springs engaging the ends 5 of said shaft and tending to move said roller toward said plunger, said switch arm having two sets of oppositely yielding contact arms arranged in arcs of concentric circles and extending parallel to the axis of said plunger, 10 the free ends of said yielding arms being adapted to engage the opposite sides of each of said stationary contacts, said stationary contacts being arcs of a circle.

6. In a switch, the combination of stationary contacts, adapted to be electrically con-

nected to circuit conductors, a movable cup shaped switch arm for electrically connecting and disconnecting said contacts, a support inside said cup shaped switch arm secured to the bottom thereof, an anti-friction 25 roller carried by said support and moving longitudinally therewith, but having a transverse movement independent thereof, springs for forcing said anti-friction roller toward the center of said cup shaped switch arm, a 30 plunger passing axially through said switch arm, a cam having oppositely inclined cam surfaces carried by said plunger and engaged by said anti-friction roller, and means for actuating said plunger.
